DEVICE FOR BORING THE LOCKHOLES
IN DOORSCarl Gellert and Fred Gellert,
San Francisco, Calif.

Application December 9, 1949, Serial No. 131,978

2 Claims. (Cl. 144—93)

1

This invention relates to door finishing machines and more particularly to apparatus for finishing a stock door for installation in a door frame.

As well known, the general type of stock doors, and particularly those employed in residence construction, are received from the mill generally dimensioned in two-inch multiples, both in length and width. Thickness usually varies from 1½ inches to 1¾ inches for interior doors. In a large construction project a great many doors are required and it is therefore important that finishing of stock doors be standardized and accomplished mechanically.

As the doors come from the mill to a builder, the opposite planar faces are finished and sanded and need no further woodworking operations. However, the outer opposite edges of the stiles are not usually precisely square with the top and the bottom edges of the door, and in fact the door is usually made a trifle more than the desired finished width, and of substantial excess length, so that proper trimming may be made to predetermined dimensions of length and width. The door also lacks a bevel at its free or lead side edge to accommodate the arcuate swing of that edge into the jamb and against the usual stop strip. Obviously the door lacks finishing for lock and hinge hardware, since these facilities are according to the preference of the individual builder.

The present invention comprises an apparatus for finishing a door ready for installation in a door frame, by transit of the door through the apparatus while its lead edge is aligned against a longitudinal guide means. In the present exemplification there are two platforms or tables in general longitudinal alignment. At a first platform or edging table the longitudinal side edges of the door are shaped, while at a second platform or sawing table the door is trimmed for length and finished for installation of facilities such as lock and bolt and hinge. Since finished doors are desired of varying widths, transversely adjustable means are provided for trimming of the longitudinal side edges, and adjustable stop means are provided for varying the length of doors. In transit the opposite side edges of the door are engaged by blades of cutters or shaper heads and thus trimmed to precisely the same width throughout the length of the stiles of the door, the cutter at the lead edge of the door having a vertically inclined blade so that it effects a bevel cut at the lead edge.

Intermediate the ends of the tables there are two sets of rollers, each set comprising a pair of roller members transversely of the first or edging

table, and having the rollers of each pair relatively spaced one above the other to receive the door therebetween during the advancement of the door between edge shaper heads, one of the rollers in each pair being a driven roller and the other being an idler tensioned to maintain the door pressed downward against the driven roller, these rollers being adapted to urge the door towards the aligning guide rail.

The sets of transverse rollers advance the door to a second or end-sawing table, the top of which is slidable transversely. At each of the opposite ends of the sliding table top is a rotary saw which trims the ends of the door squarely to the previously trimmed side edges when the table top is moved transversely against the saws. After the ends of the door are trimmed, the slidable top of this second table is returned to its original alignment with the first table.

The guide-rail edge portion of the second table has an inset cutout portion removed to receive within the inset a means for locking the door at a fixed position. At this locking device there is a rotary bit which may be elevated to drill a lock hole through the door. This locking means also includes a bracket having dowel guides or sockets to receive dowel pin guides of a bolt hole template having a bit for drilling a bolt hole into the lead edge of the door in proper relation to the lock hole. After drilling the bolt hole the same dowel guide sockets may be employed to receive dowel pin guides of a second template for routing the lead edge of the door adjacent the bolt hole for receiving a face plate for the bolt.

After squaring the top and bottom edges of the door and drilling for the lock and bolt which are effected while the door is co-planar with the table top, the door may be shifted to a vertical plane longitudinally along the side of the table with its lead edge pressed against supporting brackets and its rear or hinge edge upwardly, whereupon recesses may be routed out by suitable templates for hinge butts. If desired, hinge butts may be conveniently attached to the rear edge of the door while it is so mounted lengthwise against the vertical side of the table.

One form in which the invention may be embodied is more particularly described in connection with the accompanying drawings in which:

Fig. 1 is a side elevation of the invention, broken at portions of its length.

Fig. 2 is a plan view of the invention, broken at portions of its length.

Fig. 3 is an enlarged vertical transverse section on line 3—3 of Fig. 1.

Fig. 4 is a fragmentary longitudinal vertical section on line 4—4 of Fig. 2.

Fig. 5 is an enlarged vertical transverse section on line 5—5 of Fig. 2.

Fig. 6 is an enlarged transverse vertical section on line 6—6 of Fig. 1.

Fig. 7 is a fragmentary enlarged transverse vertical section on line 7—7 of Fig. 1.

Fig. 8 is an enlarged transverse vertical section on line 8—8 of Fig. 5.

Fig. 9 is a wiring diagram of circuits.

Figs. 10, 11 and 12 are perspective views of templates.

Referring to the drawings in which like reference characters indicate corresponding parts in the several views, 10 indicates a suitable supporting elongated base above which is spaced a first or edging table, generally indicated 11 and a second or end-sawing table generally indicated 12, the tables being generally in relative longitudinal alignment as a unit for finishing operations on a door. The tables are supported by any suitable upright supports 13 and 14.

One longitudinal side of the edging table frame has a fixed longitudinal horizontally planar platform strip portion 15 having an upstanding guide rail member 16 the entire length of one outer edge, the inner face of the guide rail being perpendicular to the plane of the platform 15 up to a shaper head to be described, the guide rail being chamfered as at 16a beyond the shaper head. A cross thwart 17 may brace the edging table frame transversely at its end adjacent the end sawing table, and in effect is a co-planar part thereof.

Parallelly spaced from the fixed longitudinal platform 15, the edging table is provided with a substantially parallel transversely adjustable elongated strip platform 18, the upper face of which is co-planar with the upper face of fixed platform 15, the adjustable platform terminating at one end short of the cross thwart 17 as at 19, and being substantially co-terminal in length with fixed platform 15 at the opposite or free end 1. The apparatus is free of cross members between the two platform strips adjacent to the last mentioned initial terminal end, providing free space between the platform strips for an operator conveniently to manipulate a door upon the platforms.

The integral continuity of the platform strips 15 and 18 is interrupted by transverse spacer gaps therein as at 20. At the gaps 20 there are provided a plurality of sets of transverse rollers, the sets of rollers being relatively spaced longitudinally of the platforms for propelling a door. Two sets of these rollers are conveniently effective for doors of accepted average length. Each set of rollers comprises a pair of horizontal roller members parallelly spaced relatively in a vertical plane, one of the rollers in each pair being an idler pressure roller 21 and the other being a driven roller 22, the driven rollers being rotated by a belt train 23 from a conventional variable speed motor 24, operated by a switch 25 positioned on the under face adjacent the free or initial end 1 of the adjustable platform strip 18 where it is conveniently manually operable by the operator as he places a door on the edging table.

Each driven roller 22 has its circumferential roller face extended a trifle above the upper face of the platform strip sufficiently to frictionally engage the face of a door resting on the platform strips. The upper or pressure rollers 21 each has its circumferential roller face normally spaced

from the drive roller substantially the thickness of a door, this spacing being adjustable and tensioned by mounting the shaft of the roller at its ends in bearings which are mounted in plate 26 vertically adjustable in tracks 26a and tensioned downwardly by springs 27. The shafts of the rollers are supported at the opposite ends thereof by bearings in supporting frames 28. When a door is being propelled by the rollers it is constantly urged toward the face of the guide rail 16 for which purpose the axis of each of the rollers is not exactly perpendicular to the inner face of guide rail 16, but is imperceptibly angular thereto in a horizontal plane, between one-half and one degree being sufficient, as indicated in Fig. 2 by an arbitrary spacing 31 relative to cross brace 17. The faces of all the rollers are covered with friction grip material such as rubber composition and may have a helical rib 32 pitched to also continually urge a door on the table towards the guide rails. Further means for initially urging the door toward the guide rail 16 and aligning the door for feed to the rollers comprises an edge-engaging roller 33 mounted on a pivoted spring tensioned lever 34, mounted on the upper face of adjustable platform 18.

The movement of the transversely adjustable platform strip 18 is accomplished by a suitable transversely slidable carriage 35 upon which the platform is mounted. The carriage as exemplified herein comprises a pair of spaced vertical plates 36, 37 appropriately connected by cross strips 38. The plates of the carriage, intermediate their height, are slidably mounted to ride on a pair of spaced transverse shafts 39 which have opposite ends mounted in fixed supporting plates 41, 42 adjacent opposite sides of the supporting frame of the apparatus. The bottom edge of the carriage plates 36, 37 are stabilized by slidably engaging transverse relatively spaced angled tracks 43. Both of the carriage plates are provided with openings therethrough as at 44 and in one or both of the openings is mounted an internally threaded flanged collar 45. A complementally threaded shaft 46 extends through and is engaged in the threaded collar, the opposite outer end of the shaft being rotatably journaled as at 47 in a frame support, said shaft being provided at its outer terminal end with the wheel crank and handle 48, whereby shaft 46 may be rotated for moving the carriage 35 and platform strip 18 transversely of the edging table and thereby adjusting the relative spacing between the door supporting platforms 15, 18, for doors of varying widths. As a convenience, a suitably calibrated scale 50 may be mounted transversely of the supporting frame adjacent the shaft 36, and the carriage 35 may carry a pointer indicator 51 by which a predetermined finished width may be set for a door, the pointer being positioned in the vertical plane of the cutting blade of an edge trimmer which will be further described.

Each of the platform strips 15, 18 is provided with a cutter means to trim the side edges of a door which is being propelled lengthwise of the edging table between the rollers 21, 22. Such means consist of a shaper head assembly mounted in each of the platforms 15, 18, the assembly 52 in platform 15 being fixedly mounted to the supporting frame, and assembly 53 in adjustable platform 18 being mounted on carriage 35 to move transversely with the carriage and adjustable platform 18. The shaper head assemblies each comprise a vertically disposed bearing 54 and a vertically disposed drive shaft 55 therein driven

at one end by a pulley 56, belt 57 and motor 58, both motors being connected by suitable circuit for simultaneous operations by switch 60 conveniently mounted at the under face of the free initial terminal end 1 of the platform strip 15 where it is convenient for operation by an operator when he places a door upon the edging table. The opposite end of each shaft 55 extends through an opening 66 in the respective platform strips 15, 18, and each shaft securely mounts a generally cylindrical shaper head for rotation therewith. The shaper heads are separately designated 61 and 62 since they have specific differences.

Each of the shaper heads has a plurality of cutter blades 63, 64 about its circumference. The blades 63 of the shaper head of the assembly 53 which is carried by adjustable platform 18, being adapted for edging or trimming the butt or hinge edge of a door, having cutting edges vertically parallel with the axis of its shaft and perpendicular to the plane of the door, whereas the cutting edges of the blades 64 of shaper head 61 of the assembly 52 which are adapted for trimming and edging the lead or swinging edge of the door, are vertically inclined relative to the axis of its shaft and the plane of the door, whereby the lead or swinging edge of the door is slightly bevelled on an angle of approximately 5 degrees to accommodate the arcuate swing of that edge into a door frame.

As heretofore stated, the inner face of the guide rail 16 is complementally bevelled beyond the shaper head as at 16a, so that as the door progressively moves through the apparatus the bevelled door edge will have continuously firm support and alignment. Since the door rides co-planar with the platforms 15 and 18 the shaper head assemblies are so mounted that the cutting edges of the blades rotate with clearance of the edges of the platforms, spacer members 65 filling the gap of platform thickness in the opening 66 through the platforms through which the shaper head assemblies are mounted.

When the carriage 35, movable platform 18, and its shaper head 53 have been adjusted to a predetermined spaced relation to the fixed platform 15, they may be locked in such a position by a suitable lock 74. Each shaper head is preferably enclosed in a guard and chip remover 75 which is a hollow box or shell having top and side wall, open at its bottom 76 so that the chips and trimmings from the door may be prevented from dispersion about the apparatus and may be exhausted to the floor through the open bottom 75.

Connected at the end of the edging table 11 as an operative continuation thereof, is the sawing table 12 for transversely finishing the ends of the door, and for the performing thereon of other finishing operations to be described.

The end-sawing table 12 likewise is supported on base 10 and has suitable vertical supports 13, 14. The bevelled portion 16a of the guide rail 16 is continued in uniform longitudinal alignment throughout the length of the frame of the sawing table 12. The sawing table is provided with a top 80 the upper face of which is in the same horizontal plane as the upper faces of the platforms 15 and 18 and the base of the bevelled guide rail 16a. This table top is an elongated rectangle of a length and width suitable to receive thereon a door of normal height and width for example, 3 ft. x 7 ft. being sufficient though it is not intended to limit the invention to specified dimensions. The table top 80 is spaced by a slot 81 from the adjacent end of the edging table

to provide space for operation of a saw to be described. At its elongated side edge adjacent the bevelled portion 16a of guide rail 16, the table top 80 is provided with a planar inset 82 which is elongated and generally rectangular. To the same edge of the table top there is secured angled flanges or fingers 83 relatively spaced from the opposite ends of the inset 82 and having a flange upstanding from the plane of the upper face of the table to approximately the thickness of a door, the inner face of one leg of the fingers being inset flush with the face of the table and the angled upstanding flange thereof corresponding to the bevel of guide 16a. The upper face of the edge 15 of the table top which has the recess 82 therein is aligned to superficially snugly contact the base of the bevelled face of guide rail 16a, and, as shown in Fig. 8, recesses in the guide rail receive the upstanding flanges of the fingers 83.

The table top 80 is mounted freely slideable transversely of the supporting frame by grooved rollers 84 mounted at opposite ends of roller shafts 85. The table top is maintained in transverse sliding alignment by track rails 86 adjacent its opposite ends, the tracks being engaged in the roller grooves. The excursion of transverse slidability of the table top is limited in both directions by hook members 87 which engage the shafts 85 and limit the movement of the shaft therebeyond, the amplitude of movement being sufficient to present the opposite ends of a door simultaneously to rotary saws 88 at opposite ends of the sawing table 80.

It will be noted that one of the saws rotates in the saw slot 81 between edging table 11 and sawing table 12, whereas the other saw rotates closely spaced beyond the opposite or terminal end of sliding table 80. The opposite ends of table top 80 stop short of the saws to permit the ends of a door, when on the table top, to overhang the ends of the top and be engaged by the saws.

The rotary saws 88 are mounted on a rockable saw frame generally indicated 90 comprising a relatively heavy beam such as a channel iron 91 extending longitudinally centrally of the table and rockably over-balanced downwardly on journaled pivots 92 at its ends, and optionally also between its ends. Each opposite end of the saw frame has an arm 93 extended perpendicularly from its longitudinal beam, the arms each having a free end adjacent the saws 88; that is, said arm extends towards the rear longitudinal side of the supporting frame. At their respective free ends each arm has suitable journalled bearings 95 for a saw shaft 96, upon the end of which adjacent the end of the table top 80, is mounted one of the saws 88. The opposite end of each of shaft 96 mounts a pulley 97 for a belt 98 driven by motor 99, the motor being mounted on the beam 90 overlying the pivot 92.

Normally the saw frame is maintained by any suitable balance means such as tension spring 100, at a position wherein the toothed circumference of the saws is entirely below the face plane of the table top 80. When it is desired to trim the ends of a door on the table, the frame may be rocked by foot pedal 101 connected by suitable jointed links 102 to tilt or rock the entire saw frame assembly including motors 99 and saws 88. Since the saws are mounted on the radius of arms 93 they are thereby elevated so that the toothed circumference is above the plane of the table top 80, whereupon a conveniently and appropriately guarded electric switch

103 may be closed to both motors 99 to drive both the raised saws simultaneously.

While the saws are raised and rotated, the table top having a door resting upon it may be moved transversely towards the saws, and the 5 portions of the opposite ends of the door extending beyond the end of the saw table top are thereby severed by the saws to finish the door to a predetermined length, the flanged fingers 83 of the table top maintaining the bevelled lead 10 edge of the door while the table top is being slid transversely and the sawing operation effected.

In sliding the table top and door thereon for the sawing operations, it may be desirable to provide means to start the sliding movement of the table top from the exterior side of the guide rail, in order to protect the fingers of the operator. Such means is here provided by a plate 104 facing the exterior side wall of the guide rail 16 and having pins 105 slidably extending 15 through the guide rail to bear upon the abutting edge of the table top, the pins being of a length that the plate is pushed outward from the guide rail when the table top is in contact with the inner face of the guide rail, and therefore it is 20 only necessary to push the plate in against the wall of the guide rail in order to start the transverse movement of the table top.

Suitable stop means are provided at the terminal end of the sawing table against which a door 30 may strike when initially delivered to the sawing table. In this connection it is to be noted that stock doors when received usually have the side stiles extending beyond the top and bottom of the transverse rails. Yet it is desirable to measure door lengths from the top rail to the bottom rail rather than from the top of the stiles which are of irregular length, sometimes varying quite substantially. Therefore the stop means is adapted to be engaged by the top edge of the top cross rail of the door. Yet the stile, usually 35 extending beyond the top rail, would engage the stop member when the door and table top were moved transversely for sawing, for which reason a stop means is provided which swings away from contact with the door rail when the saws are raised to sawing position, at which time the transverse movement of the door and the table top is accomplished.

An exemplified form of stop means comprises a vertically angled bar 106 mounted at its lower end to the tiltable beam 91 of the saw-frame. The upper end of bar 106 is normally maintained in door-stopping relation closely spaced from the adjacent end of table 80, but when the pedal 101 is pressed to raise the saws, the upper end of the stop bar is swung in an arc forwardly and downwardly away from the table end to the position shown in broken line in Fig. 6, whereupon the extended end of the adjacent stile of the door on the table may pass the stop member without interference. Upon release of the pedal the saw frame and saws return to normal downward position and the stop member returns to normal stopping position at the end of the table.

There are certain types of doors, particularly in residential buildings, which are desired of shorter length than the usual room-to-room or closet door, such as doors which must be swung over extra thick or padded rugs and carpets, and bathroom or kitchen doors which may be swung over tiled floors where the plane of the floor is higher than the usual room floors or door treads. In that event it is desirable to make a saw cut of a strip of greater width from the bottom of

the door. This may be accomplished by first sawing the ends of the door in the usual manner to obtain a finished and squared top edge and then moving the door longitudinally on the table in the direction of the saw in the slot 81, to the extent of the desired additional cut from the bottom rail of the door. This additional cut is usually of a uniform width which may be measured from the top of the door by a pivoted stop finger 111 mounted at the upper end of the stop bar 106 which may be swung on its pivot to overlie the table top as shown in dotted line in Fig. 2. Since this auxiliary stop finger which overlies the table top 80 is pivotally mounted it does not interfere in any way with the sliding of the table top to effect the additional saw cut at the bottom, because raising the saws for making such additional saw cut moves the stop bar 106 arcuately forwardly and downwardly away from the terminal end of the table, and if the extended auxiliary stop finger should strike the table it would merely be kicked out of the way. However, in normal operation there would be no such interference by the auxiliary stop finger 111, because an operator would flip it on its pivot out of any such interference after it has been employed to position the door at a predetermined position for the extra saw cut of the bottom edge of the door.

The saw cuts of the ends of the door square the door at right angles at top and bottom relative to the trimmed side edges, since the side edges have been trimmed relatively parallel by the shaper heads, and the trimmed edges are continually maintained squarely perpendicular to the end cut of the saws by the guide rail 16 and by the flanged fingers 83 which latter have the same alignment as the guide rail and move with the table for maintaining the door alignment during the end-sawing operation.

Means are provided at the sawing table 12 for appropriately cutting holes for a lock, a bolt, and a recess for a bolt plate and for routing recesses for mounting hinge butts. As previously described the bevelled face portion 16a of the guide rail extends along the front edge of the supporting frame and therefore confronts the adjacent front edge of the table top 80 which has the inset 82 therein. Within the planar dimensions of the inset 82 there is mounted on the supporting frame of the table 12 a door-clamp generally indicated 120, and a rotary circular bit assembly generally indicated 121. The clamp 120 is for gripping and holding the door while the bit apparatus is operative to drill a hole for a lock.

The clamp comprises a vertically movable clamping plate 122 and a fixed clamping plate 123 which are relatively spaced horizontally parallel. Each of these plates has a central opening therethrough 122a and 123a. As shown herein, the fixed plate 123 is uppermost, whereas the movable clamping plate 122 is normally coplanar with the upper face of the table top 80, or slightly therebelow sufficient to permit clearance for a door sliding on said table top. These clamping plates and the boring bit apparatus may optionally assume any one of three relationships, only one of which is illustrated herein, since the other forms would merely be a transposition of operative parts. In one form a movable plate 122 may be uppermost and move downwardly toward a fixed plate 123 at the table level, the bit apparatus being therebelow; in another form the fixed plate 123 may be at table level, the moving plate 122 thereabove and the boring

bit apparatus mounted above the upper plate to operate downwardly; the third form being illustrated herein in which the plane of the movable plate normally coincides substantially with the plane of the table top 80 and the bit apparatus is therebelow, this form being adopted in the present exemplification merely because it was convenient in connection with other structural factors.

The fixed clamping plate 123 is suitably supported on the frame in a plane parallelly horizontal to the movable plate 122 and spaced above the normal plane of the movable plate and the table top for a greater distance than the thickness of a door to be operated thereupon; therefore, it is obvious that the fixed plate is above the necessary height of the bevel 16a of the guide rail 16. The support for the fixed plate 123 comprises braces 124 inclined upwardly and outwardly, the incline thereof permitting a shorter interruption or break in the continuity of the guide rail than if the braces were perpendicular to the table and spaced the full length of the fixed plate. The lead edge of the door is accessible through the opening between the inclined braces so that other operations may be performed on the lead edge.

In the central opening 123a of the fixed plate there is a perpendicular tubular collar member 125 secured thereto by pipe flange 126, the lower end of the collar having a sharpened edge 127 slightly protruding beyond the bottom of the plate 123 sufficiently, however, merely to indent or bite into the face of the door circumferentially of a lock hole to be bored therein and thus prevent splintering around the board hole when a bit breaks through by a cut from the opposite side of the door.

The movable clamp plate 122 is supported upon a bracket having sleeves 128 which are reciprocable upon vertical rods 130 suitably fixed upon the frame as at 131, the plate with the door resting thereon being elevated by a train of links 132, responsive to a handle lever 133 which at elevated position may be engaged in lock 134, and thus hold the door slightly elevated from the table top 80 and against the fixed plate 123, with the sharpened edge 127 of collar 125 biting a circle into the opposite face of the door stile, the plate being lowered by weight of the door when the handle is released from the lock, though the handle may be employed to positively lower the plate, if desired.

The circular bit assembly generally indicated 121 comprises a motor unit 135 having chuck 136 mounted for rotation by the motor shaft, the chuck engaging for rotation the shank of a circular wood bit 137. The motor shaft, chuck and rotary bit are coaxially aligned with the collar 125 and preferably also with the opening 122a of plate 122, though this latter is not essential so long as the opening 122a is sufficiently large to receive the bit therethrough with suitable clearance. The bit unit 121 is mounted for vertical reciprocation by brackets 138 which are slidable upon shafts 130, the reciprocation being responsive to link train 140 responsive to manipulation of lever handle 141, a suitable switch 142 being conveniently carried by the motor 135. A bumper member 139 may support the bit assembly at rest or cushion the impact of lowering it. It is believed obvious that plate openings 122a, 123a and collar 125 and its sharpened edge 127 are of a greater diameter than circular bit 137 and sized to sufficiently clear the teeth of the

circular bit which must pass therethrough, the thrust pressure of the clamp plates and the boring bit being removed from the table top and its slide mechanism during the gripping of the door and the boring of the lock hole and the indenting or biting into the surface of the door by the annular sharpened edge 127.

Means are carried by the fixed plate 123 for positioning of templates for drilling a bolt hole into the edge of the door and into communication with the lock hole, and for also holding another template for recessing the edge of the door for a bolt plate. Such means may consist of a pair of relatively spaced sockets 143 fixed to the upper face of the fixed plate 123 for snugly slidably receiving pins 144 which are mounted on a template 145 having a properly spaced tubular guide 146 for a wood bit 147 for drilling the bolt hole in the door edge. Upon removal of the bolt hole template 145, a second template 148, having a suitably shaped opening 150, may be mounted against the edge of the door exposed between the inclined braces 24 and suitably positioned by similar pins 151, whereupon a suitable router machine may be employed through the opening of the template to rout a recess for a bolt plate in the door edge.

The door having been finished at its side edges and ends, and having the lock hole, bolt hole and bolt plate recess made therein, may be conveniently lifted manually from its bed on table top 80 and slid to overlie the front wall of the supporting frame with its lead edge resting in fixed brackets 152; or if it be a transversely narrow door, by resting said lead edge in brackets 153 which are slidable inwardly and outwardly on the frame, the vertical positioning of said brackets being arranged so that the rear or butt edge of the door is thus spaced above the top edge of guide rail 16. It is practically immaterial whether the rear or butt edge of the door is thus spaced above the upper face of the fixed clamping plate 123, because the operation performed at this position is the routing for hinge butts which are almost invariably adjacent the opposite ends of the door and seldom at a vertical central portion of the door, except in unusually thick and heavy entrance doors. The door having been mounted in the brackets, either 152 or 153, an elongated template 154 of suitable length having side gripping flanges 155 is placed lengthwise of the butt edge of the door, the template having predetermined spaced openings 156 therein through which the same or a similar router tool as previously referred to may be employed to rout recesses for hinge butts. If desired, the hinge butts may be mounted on the door at this position, thus leaving only one complementary butt to be attached to a door jamb when the door is hung.

In this connection it may be stated that it is not usual practice to mount locks and bolt hardware in a door until the door is mounted in its frame, since such hardware usually has a refined metal finish and is usually not installed until after liability to damage or breakage is past.

In operation the door *a* is manually placed upon the platforms 15 and 18 of edging table 11 with its lead edge *b* against the face of guide rail 16, which will automatically align the lead edge for cutting engagement by the bevelled shaper head 51. The crank wheel 48 is rotated to adjust the platform 18 transversely until the pointer 51 registers on scale 50 the predetermined or desired width of finished door. At an initial step of man-

ually feeding the door towards the first set of conveying rollers 21, 22 the lead edge *b* is continually urged toward the face of the guide rail by the spring tensioned roller 33 bearing against butt edge *c*. After the door has been engaged by the first set of rollers 21, 22 the lead edge *b* is continually urged towards the guide rail by the successive sets of rollers, as described. As the side edges *b* and *c* pass the rotating shaper heads these edges are trimmed to the predetermined scale width, the blades 63 trimming the butt or hinge edge *c* perpendicular to the plane of the door, and the blades 64 trimming the lead edge *b* to a corresponding chamfer *d*, after which the chamfered edge *d* bears against the complementally bevel face 16a of the guide rail. The refuse cuttings are thrown through the bottom openings of the chip remover 75.

As the edges *b* and *c* are progressively trimmed, the second set of rollers 21, 22 propel and transfer the door to the top 80 of sawing table 12, the door having transverse support during the advancement and transfer by the plane of the cross brace 17. It is preferred that the second set of rollers release the door prior to the engagement of the top of the door against the stop 106 or 111, as the case may be, since experience has demonstrated that in view of the somewhat irregular length of door stiles and the desire for accurate sawing at the ends, it is more practical to make manual adjustment of the door for the final few inches to abut the stop member and insure snug contact of its bevelled edge against the bevelled face 16a of the guide rail. It is to be understood that when advancing the door to table 12 the movable plate 122 is substantially co-planar with table top 80 so that the door may readily slide thereover, the door being positioned with edge *e* of its top rail against the stop member.

At this stage of operation, precedence may be given either to the sawing of the ends of the door or the operations performed at the clamping assembly 120, such as boring the lock and bolt holes, the operations being successive regardless of which is effected first. As a matter of choice, it is preferred to perform the operations of the bit assembly 121 first and thereafter saw the ends of the door, since after sawing the ends of the door it is convenient to tip the door on its side edge for routing the rear edge for hinge butts.

The door having been positioned on the table top 80 against stop 106 and with its chamfered lead edge *d* against the bevel 16a of the guide rail, the movable lock plate 122 is, in the present example, manually raised upwardly by operation of handle lever 133 whereby the door overlying the plate is bodily raised in its entirety from the table top and clamped against the fixed plate 123 and maintained so raised and clamped by engaging the handle lever 133 in the lock 134. It will be observed that the lead edge of the door is exposed through the opening between the inclined brackets 124. With the door at this position, the bit switch 142 is closed to operate motor 135 and thereby rotate the circular bit 31, whereupon the handle lever 141 is manipulated to raise the bit through the plate opening 122a and cut the lock hole *f* in the door, the sharpened circular edge 127 of the collar biting into the opposite face of the door around the cut hole and preventing splintering around the edges of the cut as the bit breaks through. The opening of collar 125 permits the bit teeth to break through without striking foreign objects and also serves to

further prevent injury to an operator from the high speed of the bit. The lock hole *f* having been cut the handle lever 141 is released and the bit assembly will return to its downward position by gravity, or if desired, it may be lowered by means of the handle and gently contact bumper 139.

While the door remains locked in the clamp the pins 144 of the bolt hole template 145 are mounted in the sockets 143 which accurately positions the bit 147 to cut the bolt hole *g* into the side edge and into communication with the lock hole. Having cut the bolt hole, the second template 148 is similarly mounted by pins in the sockets 143 and a router blade inserted through its opening 150 to rout a recess in the door edge for a bolt face plate.

After the aforesaid operation at the clamp plates, the clamp is released and the door returned to lay freely upon the table top 80 with the edge *e* of its top stile against the stop member 106, and its bevelled edge *d* squared against the guide rail 16a, whereupon the foot pedal 101 is depressed which rocks the saw frame 90 on its pivots 92 and thereby simultaneously raises the saws 88 at opposite ends of the table top, so that the cutting edges of the saws are above the table top and moves the stop member 106 out of the way of the extended end *h* of the stile. With the saws raised the switch 103 is closed to operate both motors 99 simultaneously, whereby the saws are rotated in unison. Obviously, if desired, the switch 103 may be automatically closed by the raising of the saws, by mere mechanical expedient of placing the switch close to the saw frame and a trip on the frame or pedal to close the switch to rotate the saws. While the saws are raised and rotating the table top 80 and door thereon are slid upon the rollers 84 towards the saws which trim the top *e* and bottom *i* to the predetermined length, the hooks 87 being operative to engage the roller shafts 85 to limit the sliding transverse movement of the table top. As previously stated, a second cut may, if desired, be made at either end of the door by retracting the table top, shifting the door thereon a desired distance longitudinally and making the desired end cuts. It will be noted that the flanged fingers 83 at the edge of the table top travel with the table top and maintain the same squared alignment of the door as previously accomplished by the bevelled face 16a of the guide rail. After the sawing operation, the foot pedal is released and the saws are returned to their lowered position by gravity and tension of spring 100.

When the ends of the door have been sawed and the table top retracted, the door may be manually lifted from the table and its lead edge *d* slid into the bracket 152 or 153 (depending on the transverse width of the door), with the plane of the door parallel to the front side 3 of table 12. Such position disposes the rear or butt edge *c* of the door upwardly. The elongated template 154 is placed upon the rear or butt edge *c* of the door and the router machine employed through appropriately spaced openings 156 to rout recesses for hinge butts, and if desired one butt of each hinge may be secured to the door while so positioned.

The bit 147 employed with the bolt hole template 145 as well as the routers may be driven electrically.

Having described the invention, what is claimed as patentable is:

1. In a door finishing apparatus having a

table top for receiving a door flatly thereon, means adjacent one edge of the table top for boring a lock hole through a door on the table top, including a clamp plate inset into an adjacent edge of the table top substantially co-planar with the table top, another clamping plate spaced overlying and parallel to the first mentioned plate, said clamp plates each having an opening therein, a boring bit reciprocable through the openings in the clamp plates and through the plane of the table top, the opening of the clamp plate most remote from the bit having an annular sharpened edge extending from the face of said remote clamp plate for biting into the door face which is opposite the boring bit, the opening of said remote clamp plate and the annular sharpened edge thereof being of sufficiently greater diameter than the bit to provide sliding clearance therebetween.

2. In a door finishing apparatus having a table top for receiving a door flatly thereon, means adjacent to one edge of the table top for boring a lock hole through a door on the table top, including a clamp member opposed to one face of the table top for holding a door in flat relation to the table top, said clamp member having an opening therethrough and an annular sharpened edge around said opening extending from the clamp member toward the table top, and a boring bit at the opposite face

5
10

of the table top and axially aligned with the annular sharpened edge, said bit being reciprocable through the plane of the table top and door thereon and through said annular sharpened edge and clamp opening, said annular sharpened edge being adapted for biting into the face of the door opposite the bit when the door is engaged by the clamp, and being of a diameter sufficiently greater than the diameter of the bit to permit the bit sliding clearance therethrough.
